UNITED STATES PATENT OFFICE

EDMUND A. BALTZELL, OF PORTLAND, OREGON

SHARPENING DEVICE

Application filed January 12, 1929. Serial No. 332,102.

The primary purpose and object of my device is for the sharpening of shears, scissors, snips and other two bladed cutting implements that consist of a pair of blades with handles, and pivoted face to face so that the opposite edges may be brought together on the object to be cut.

The device is composed of a body element having two sharpening faces spaced apart between which the blade to be sharpened may be clamped. The sharpening faces of the body element are made of a hard material, as case hardened steel, to resist the filing action or the honing action. The sharpening faces are beveled and in alignment. The purpose of this is to enable an inexperienced operator to positively sharpen the cutting faces of the scissors to an accurately and true beveled edge.

One of the objects of my device is to provide an efficient device inexpensive at first cost and through the use of which an inexperienced operator can maintain the cutting faces of the scissors or cutting implements in first class operating condition.

A further object of my device resides in a simplified construction adapted to being held in the hand of the operator for sharpening and having associated therewith a simple clamping device for clamping the blade within the device to be sharpened and having a true hardened bevel surface that enables the sharpener to reduce the cutting edge of the cutting implement to true bevel and alignment.

A still further object of my device is to provide means to hold scissors and the like while being honed or otherwise sharpened, whereby the blades are clamped in certain predetermined positions with relation to each other.

Another object of my device is to eliminate the possibility of ruining the bevels at the cutting edges of the instrument being sharpened, which is an important and essential element to maintain. The aligned beveled edges of the side walls of my sharpening device provide a correct and positive sharpening angle by which the instrument to be sharpened is enabled to maintain the

proper beveled edges irrespective of the inexperience of the operator.

A further object of my device resides in beveling the edges of the side walls and aligning them for the purpose of providing a positive sharpening angle for guiding the abrading element and for preventing the application of the abrading element upon the edges of the instrument being sharpened longer than is necessary or desirable for the proper maintenance of the beveled edges of the instrument.

A still further object of my device resides in making the beveled surfaces of material adapted to resist abrasives and enabling the device to have at all times a true beveled surface thereby providing accurate means by which the cutting edges of the cutting instrument can be sharpened without the possibility of spoiling the beveled edges of the cutting element.

A further object of my device is to provide means whereby the operator may be guided in aligning the cutting edges with the beveled edges of the device without undue loss of time and effort.

With these and incidental objects in view, the invention consists in certain novel features of construction and combination of parts, the essential elements of which are set forth in the appended claims, and to a preferred form of embodiment of which is hereinafter shown with reference to the drawings which accompany and form a part of this specification.

In the drawings:

Fig. 1 is a perspective end view of the device illustrating a pair of scissors clamped within the device.

Fig. 2 is a longitudinal, sectional view, taken on line 2—2 of Fig. 1, looking in the direction indicated. The line of sight is shown in dotted position to illustrate the purpose of the line disposed longitudinally of the blade to align the blade with the surface over which the file or hone is made to pass to reduce the cutting edge to bevel and alignment.

Fig. 3 is a side view of the assembled device.

Fig. 4 is a top, plan view of the mechanism, illustrated in Fig. 3.

Fig. 5 is a longitudinal, sectional view, taken on line 5—5 of Fig. 4, looking in the direction indicated.

Fig. 6 is a cross section view, taken on line 6—6 of Fig. 3, looking in the direction indicated.

Fig. 7 is a perspective, rear view, of the assembled device, the same being made to illustrate the off-set disposed within the side wall, to accommodate the shear blade, being sharpened, that is disposed within a depression that is disposed in the oppositely disposed side wall of the body element.

Fig. 8 is a rear side view of the device, illustrating the off-set in the rear side wall against which the blade to be sharpened is clamped against the inner wall of the side. The offset being shown to accommodate the shear blade not being sharpened.

Like reference characters refer to like parts throughout the several views.

I preferably form my device of a body element 1, having upturned side walls 2 and 3, spaced apart to permit the placing of a cutting implement blade 4, therebetween. The blade is held by any suitable clamping means, as by a thumb screw 5, the thumb screw 5 being in threaded relationship with the upturned bracket 6, disposed upon one side of the body element. I form my device having two bevel surfaces 7 and 8 in alignment, the bevels are so placed as to permit the giving to the blade to be sharpened the greatest cutting value by getting properly beveled cutting edges. An offset 9, is disposed within one of the side walls of the body element into which the blade 10 of the cutting implement not being sharpened is, or may be placed so that the surface 11 of the blade to be sharpened may be brought into intimate contact with the inner surface 12 of the side wall 3. I have found best results obtain wherein the top portion 9A is cut away to accommodate the clamping element 9B outwardly extending from the blade. In order to facilitate the placing of the blade to be sharpened in precise position, I have found good results obtain wherein parallelly disposed notches 13 and 14 are formed longitudinally of the upper surface 7 of the side wall 3, of the upper wall so that the user of the device may place the blade in alignment with one of the notches thereby facilitating the placing of the same in the manner to require the reduction of a minimum amount of the cutting blade to reduce the same to bevel and alignment. I have illustrated in Fig. 2 the use of the alignment line or notch. This enables the user to place the blade to be sharpened in position quickly and easily. A fine line placed near the inner edge of the bevel surface 7 will give excellent results and when used for blades requiring

a minimum of reduction should be used, and where the blade is in relatively bad condition one of the other lines should be used. A part of the side wall 2 is cut away, as illustrated at 15, in order that the thumb of the operator may be made to grasp the body of the device and the handle 16 of the blade not being sharpened. The cutout 17 is made to facilitate the placing of the shears or cutting implement within the device to be sharpened. After the device has been formed and trued to surface, the same is then case-hardened and more particularly case-hardened upon the surfaces 7 and 8 to prevent the reduction of the device when the cutting blade is being filed or honed. The device may be made of sheet stock, and the body portion can be made of a single piece of metal. The offset 9 should be sufficiently offset to accommodate the shears having a maximum thickness of the blade not being sharpened, in order that the cutting blade to be sharpened may be made to intimately contact against the inner wall 12, against which the blade is clamped.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow:

What I claim is:

1. In a device of the class described, the combination of a body element having a base and side walls spaced apart and extending upwardly therefrom, there being case-hardened beveled surfaces terminating the upper edges of the side walls and in registerable alignment with each other, and an offset disposed in one of the side walls for permitting the blade to be sharpened to be brought into intimate contact with the inner surface of one of said walls and to accommodate the blade not being sharpened and means for clamping the device to be sharpened relative to the body element.

2. In a device of the class described, the combination of a body element having a base and side walls spaced apart and extending upwardly therefrom, there being case-hardened beveled surfaces lying in the same plane, terminating the upper surfaces of the side walls, one of said surfaces having one or more grooves running longitudinally thereof, and an offset disposed in one of the side walls adapted to permit the blade being treated to be placed in intimate contact with one of said walls and to hold the blade not being treated, and the oppositely disposed side wall being cut away for a portion of its length and means for clamping a device to be sharpened relative to the body element.

3. In a device of the class described, the combination of a one piece body element, there being a channel running longitudinally of the body element to form oppositely disposed side walls, hardened bevel surfaces registrably aligned terminating the upper edge of each of the side walls, and one or more grooves running longitudinally of one of the bevel surfaces, one of the side walls having an offset disposed therein to receive the 10 blade of the device not being sharpened and to permit the placing of the blade being treated in intimate contact with the wall, the oppositely disposed side wall being cut away for a part of its length to facilitate 15 the admittance of the device to be sharpened within the device and means for clamping one of the blades relative to the body element.
